W. C. COX

PHOTOGRAPHIC PAPER RECEPTACLE

Filed June 16, 1920

By

William C. Cox
Burke Young

Attorney

UNITED STATES PATENT OFFICE.

WILLIAM C. COX, OF WASHINGTON, DISTRICT OF COLUMBIA.

PHOTOGRAPHIC-PAPER RECEPTACLE.

Application filed June 16, 1920. Serial No. 389,512.

To all whom it may concern:

Be it known that I, WILLIAM C. Cox, a citizen of the United States of America, residing at Washington, in the District of Columbia, have invented a certain new and useful Improvement in Photographic-Paper Receptacles, of which the following is a specification.

The present invention has reference to improvements in receptacles, more particularly to that type of receptacle employed for containing or housing bromide and other highly sensitized photographic paper, the principal object of my invention residing in the provision of a device of the character mentioned which is desirable for use by photographers for housing the sensitized paper used by them in printing work in a manner such as will positively shield the same from the action of detrimental light rays and also, to prevent such receptacle from being carelessly left open subsequent to the removal of paper therefrom.

It is also an object of the invention to provide a novel form of closure for the receptacle capable of being easily and quickly opened as may be desired, whereupon said closure will automatically move to its closed position for shielding its sensitized contents from light.

Other objects will be in part obvious and in part pointed out hereinafter.

In order that the invention and its mode of application may be readily understood by those skilled in the art, I have in the accompanying illustrative drawings and in the detailed following description based thereon, set out a preferred embodiment of the same.

In the drawings:

Figure 1 is a perspective view of my improved receptacle;

Figure 2 is a fragmentary side elevation of the same;

Figure 3 is a fragmentary vertical longitudinal section through the receptacle, and,

Figure 4 is a fragmentary detail in section taken on the line 4—4 of Figure 2.

Having more particular reference to the drawings, in connection with which like reference characters will designate corresponding parts throughout the several views thereof, 1 indicates the box proper of my improved device, the forward portion of which is open.

Hinged to the forward marginal portion of the box 1 and adapted to cover or close a portion of the forward opening therein, is a flap 2, of size and shape corresponding to that of the wall in the opposite end of the box 1, such hinge connection of the flap being effected through the medium of spring hinges 3, whereby said flap will be normally maintained in its closed position with relation to the box.

Right angularly disposed apertured tongues 4 are formed on the opposite ends of the flap 2, and as will be noted, are adapted to be arranged adjacent the side walls of the box 1 when said flap is in its closed position, and also, to have connection for effecting its opening, such as hereinafter more fully described.

As means for closing the remaining open portion of the box 1, a lid 5 is employed and is formed with side and end walls which are adapted to be engaged over that end of the box adjacent thereto whereby to effect positive closure of the same. Rearwardly disposed crank arms 6 extend from the lid 5 and carry thereon pins 7, while the rearward marginal portion of the lid is connected to the corresponding portion of the box proper by means of spring hinges 8, similar to the hinges 3.

From the foregoing it will be seen that I have provided a form of means for closing the open forward portion of the box 1, such means consisting of the hinged flap 2 and the hinged lid 5, the flap 2 being secured in its closed position with relation to the box through the engagement of the end and side portions of the lid 5 thereover.

As means for effecting connection between the flap 2 and the lid 5 whereby to facilitate opening of the box and further, to insure proper functioning of such elements, links 9 are provided on each side of said box, certain of the ends thereof having pivotal connection with the apertured tongues 4 as at 10, while slots 11 are formed in the opposite portions of said links and slidably receive the pins 7 therethrough, these pins, if desired, having their outer ends upset or headed whereby to prevent disengagement of the slotted ends of the links 9 therefrom. Thus, when the lid 5 is grasped by a user and swung upwardly about its pivot afforded by the spring hinges 8, the rearwardly disposed crank arms 6 will obviously move forward,

thus moving the pins 7 in a corresponding direction through the slots 11 in the adjacent ends of the links 9. When the lid 5 has been swung upwardly for a predetermined distance, the pins 7 on its fingers 6 will positively engage the links 9, since they will have moved to the inner ends of the slots 11 therein. At this time, and with continued movement of the lid 5, outward thrust will be imparted to the links 9 and in consequence to the hinged flap 2 by reason of the pivotal connections 10, thereby causing said flap to be swung downwardly to an open position. In this connection, it should be noted that by providing the slots 11 in the links 9 whereby movement of the lid 5 independently of the flap 2 will be permitted for a predetermined distance, said lid 5 will be allowed to swing clear of the flap 2 and in consequence, afford a clear path of movement thereto.

Strips indicated by the numerals 12 and 13 are arranged interiorly of the box 1, namely, over the connection of the flap 2 and the lid 5 with the same by hinges 3 and 8, thus affording "light breaks" for preventing passage of light rays into the receptacle with the resultant detrimental action upon its sensitized contents. Other forms of "light breaks" are provided and are in form of angle strips 14 secured to the inner side of the flap 2 adjacent its opposite ends and are adapted to be engaged in similar strips 15 arranged in and secured to the adjacent portions of the side walls of the box 1.

The use of my improved device may be reviewed as follows:

Photographic paper, usually in sheets, is arranged in the box 1 and when the photographer desires to remove one or a number of these sheets, he grasps the lid 5 and swings the same upwardly on its pivot against the tension of the springs of the hinges 8. Such movement of the lid will be transmitted to the flap 2 through the means hereinbefore set out, thus, moving said flap downwardly whereby to expose the ends of the sheets of paper in order that the same may be conveniently engaged and removed. With removal of the paper from the receptacle, the lid 5 is released, whereupon it will immediately move downwardly under tension of the springs of the hinges 8, the pins 7 moving to the outer ends of the slots 11 in the links 9 so as to permit of engagement of the lid 5 over the upper portion of said flap. It of course will be understood, that the flap 2 will close slightly before the lid 5, by reason of the provision of the slotted links 9 which are connected by the pins 7 to the rearwardly disposed fingers 6 on said lid 5, this flap moving to its closed position automatically by means of the spring hinges 3 which connect the same to the adjacent portion of the box 1. Hence, since said

flap is first moved to its closed position, it will be appreciated that the lid 5 will be allowed to engage over the same in its subsequent closure, thus positively closing the previously open portion of the receptacle 70 and preventing the admission of light to the box.

In using my improved receptacle for photographic paper, I desire to have it understood that a number of the same may be employed if desired, these different receptacles varying in size to accord with the size of the paper to be housed thereby. The different size receptacles are preferably arranged in stepped superposed relationship, the stepped portions thereof being lids 5, whereby said lids can be freely and readily swung upwardly for opening their particular receptacles. By this arrangement, it will also be noted that the lids 5 of the receptacles will be prevented from swinging back too far, and in consequence, will insure their prompt return to closed position upon release by the photographer.

Manifestly, the construction shown is capable of considerable modification and such modification as is within the scope of my claims, I consider within the spirit of my invention.

I claim:

1. A box-like receptacle having its forward end open and also having a portion of its top open adjacent to such forward end, a flap hinged to the receptacle and normally closing the forward end opening, a lid hinged to the receptacle and normally closing the opening in the top, a crank arm extending backwardly from said lid, and a link pivotally connected to said flap and having a jointed connection with the lid. 105

2. A box-like receptacle having its forward end open and also having a portion of its top open adjacent to such forward end, a flap hinged to the receptacle and normally closing the forward end opening, a lid hinged to the receptacle and normally closing the opening in the top, a crank arm extending backwardly from said lid, and a link pivotally connected at one end to the flap and having a pivoted and sliding engagement with the lid. 115

3. A box-like receptacle having its forward end open and also having a portion of its top open adjacent to such forward end, a flap hinged to the receptacle and normally closing the forward end opening, a lid hinged to the receptacle and normally closing the opening in the top, a crank arm extending backwardly from said lid, and a link pivotally connected to said flap and connected with the lid in such manner as to permit the lid to be moved on its hinge a predetermined degree before movement is imparted to the flap. 125

4. A box-like receptacle having its for- 130

ward end open and also having a portion of its top open adjacent to such forward end, a flap hinged to the receptacle and normally closing the forward end opening, a lid 10 hinged to the receptacle and normally closing the opening in the top, a crank arm extending backwardly from said lid, and a link pivotally connected to said flap and connected with the lid in such manner as to permit the lid to be moved on its hinge a predetermined degree before movement is imparted to the flap, and yieldable means for holding the flap and lid normally closed.

WILLIAM C. COX.
